UNITED STATES PATENT OFFICE.

JEREMIAH M. HOFFMAN, OF READING, PENNSYLVANIA, ASSIGNOR OF ONE-HALF TO
HENRY HOWARD HOFFMAN, OF READING, PENNSYLVANIA.

WASHING-MACHINE AGITATOR.

1,157,222.

Specification of Letters Patent.

Patented Oct. 19, 1915.

Application filed February 9, 1915. Serial No. 6,985.

To all whom it may concern:

Be it known that I, JEREMIAH M. HOFFMAN, a citizen of the United States, residing at Reading, in the county of Berks and

5 State of Pennsylvania, have invented certain new and useful Improvements in Washing-Machine Agitators, of which the following is a specification.

This invention relates to improvements in 10 washing machine agitators and the object is to provide an agitator of comparatively simple construction which may be used with equal facility in connection with washing machine tubs of various form and construction.

A principal object is to provide an agitator in which the maximum cleansing effect is produced with a minimum of effort, and to this end I have constructed a device comprising a series of vanes projecting from a common center but arranged tangential to the axis of the agitator shaft, in contradistinction to one in which such vanes radiate from said axial line.

25 A further object is to provide for a circulation of the washing medium through the agitator.

The construction shown and described is such that an alternating centrifugal and centripetal action of the water is produced, which, together with the proper circulation thereof, will materially aid in the washing effect and reduce the effort necessary to produce a given result.

35 The invention is more fully described in the following specification and clearly illustrated in the accompanying drawing, in which:—

Figure 1 is a vertical, central sectional view of a tub with my improved agitator in position therein. Fig. 2 is a sectional view taken on the line 2—2 of Fig. 1.

40 The numeral 1 designates a washing machine tub of ordinary construction, provided with a suitable cover 2.

The numeral 3 designates the agitator shaft which is mounted on the cover in a suitable support 4, and 5 designates an operating handle attached to the shaft and by 45 means of which the agitator is operated.

To the lower end of the shaft 3 I attach my agitator which comprises a cover or top piece 6 and a plurality of vanes or blades 7. The top piece is preferably secured to the

upper edges of the blades and acts as a cover 55 or top of the spaces formed between the side walls of the blades, as shown in Fig. 2 in dotted lines.

The blades of the agitator are arranged in a line tangent to the axial center line of the 60 agitator shaft, and thus form, when four blades are used as in the present instance, a substantially rectangular opening in the center, indicated by the numeral 8. The upper end of this opening is preferably closed 65 by a plug 9 to which the shaft may be more securely attached and also to serve as a closure for the space 8.

The blades are formed, each with a series of perforations 10 in their projecting ends, 70 and also with a series of like perforations in close proximity to their inner ends where they form the walls of the space 8.

The agitator is moved to and fro, producing an oscillatory movement as is usual in 75 such instances, and the clothing together with the cleansing element contained in the tub is agitated. When the agitator is moved in one direction, that indicated by the arrow in the drawing, the effect on the contents of the tub is to force said contents toward the tub wall with a centrifugal action, due to the fact that the surfaces of the blades producing the action extend to a point slightly beyond the axial center, while, 85 when the direction of the agitator is reversed, and the smaller surfaces of the blades act directly on the contents, the larger spaces behind each blade will produce a suction which will tend to draw the 90 contents toward the center of the tub, and while both of these movements are being produced, the water will circulate freely up through the center 8 of the agitator and out through the perforations in the blades. The 95 perforations in the projecting portions of the blades will permit the free movement of the agitator and also aid in forcing the water through the clothing as the agitator moves.

It is evident therefore, that with 100 the alternating centrifugal and centripetal action produced, the cleansing effect produced with a given effort, approaches the maximum, as the clothing will not be permitted to mass or become tightly rolled, 105 while the complete circulation of the water aids materially in producing the cleansing effect.

Having thus fully described my invention, what I claim is:—

1. An agitator for washing machines comprising four vertical blades joined at their inner extremities in a manner to form a rectangular space or opening, said inner ends being perforated whereby a circulation of liquid may be had through said rectangular opening.
2. In a washing machine agitator, a centrally disposed shaft, a top piece to which the shaft is attached, and a plurality of blades secured to the under side of the top

piece and arranged tangentially to the axial line of the shaft, the inner edges of which ¹⁵ blades extend beyond said axial line and form a hollow space in the center of the agitator, said blades being perforated to permit circulation of liquid through said space.

In testimony whereof I affix my signature ²⁰ in presence of two witnesses.

JEREMIAH M. HOFFMAN.
